G. L. FULLER

DEEP WELL PUMP

Filed March 27, 1922

Rid. 1.

Patented Sept. 11, 1923.

1,467,370

UNITED STATES PATENT OFFICE.

GEORGE L. FULLER, OF SISQUOC, CALIFORNIA.

DEEP-WELL PUMP.

Application filed March 27, 1922. Serial No. 547,200.

To all whom it may concern:

Be it known that I, GEORGE L. FULLER, a citizen of the United States, residing at Sisquoc, in the county of Santa Barbara and State of California, have invented new and useful Improvements in Deep-Well Pumps, of which the following is a specification.

This invention relates to deep well pumps for use in oil wells or other wells, and contemplates an improvement on the device disclosed in my Patent 1,416,277, May 16, 1922.

At the present time it is customary in deep well pumps to provide what is known as a standing valve which may be withdrawn or seated through the medium of what is known as a Garbutt rod associated with the plunger and with the standing valve. The Garbutt rod is so formed and so inter-connected with the plunger and the standing valve as to permit the plunger to reciprocate within the limits of the pump stroke without unseating the packing of the standing valve from its seat. The present invention, however, does away with the Garbutt rod and has for one of its objects the seating and unseating of the standing valve, and whereby the plunger and the standing valve may be independent of each other during the working stroke of the plunger. A further object of the invention resides in the automatic unlocking of the standing valve from the plunger.

The invention has for further objects the provision of a pump of the general character stated which will be superior in point of relative simplicity and inexpensiveness of construction, combined with positiveness and effectiveness of operation, compactness in form, economy in power and freedom from frictional loss and wear and tear, and facility in repair, and which will be generally superior in efficiency and serviceability.

With the above and other objects in view, the invention consists in the novel and useful provision, construction, formation, combination, association and inter-relation of parts, members and features, all as herein-after described, shown in the drawing, and finally pointed out in claims.

In the drawing:

Figure 1 is a fragmentary, vertical sectional view of a pump constructed and organized in accordance with the invention;

Figure 2 is a top plan view showing one

of the members of the present invention, associated with the standing valve;

Figures 3 and 4 are fragments of the member associated with the standing valve; and

Figure 5 is a plan view of the plunger nut adapted to cooperate at times with the member illustrated in Figures 1 to 4 inclusive.

Corresponding parts in all the figures are designated by the same reference characters.

Referring to the drawing, A designates the barrel member of a pump, B the plunger, C and D members which may interengage for the purpose of withdrawing the standing valve E; all of which members may cooperate in the practice of one embodiment of the invention. The members C and D may be termed interlocking or gripping members, inasmuch as they cooperate at times to withdraw the standing valve E from its seat. The member C may include the usual form of plunger nut having a screw-threaded engagement as at 1, with the plunger B. The plunger nut C, as is customary, is annular in form, and in the adaptation shown, is provided with two inwardly directed and diametrically opposed studs 2 and 3.

The standing valve E is annular in form and includes the usual crown member 4, a bearing seat 5 adapted to receive a ball or other member 6, the crown member 4 normally confining the ball member to maintain the same in position. The standing valve E likewise includes an annular body member 7 carrying packing rings 8 so as to hold the same in close engagement with an end-piece 9, said end-piece being coupled to the barrel A as by means of a ring member 10. As the pump is operated oil or other liquid is drawn into the space above the standing valve upon the up-stroke of the plunger A, rising above the working valve upon the next down stroke of the plunger, and thereafter being elevated with a column of liquid above it to produce flow at the mouth of the well.

At times it is necessary to remove the standing valve E from the end-piece 9 and in order to do this the members C and D interlock or grip each other in a manner to be described. The member D includes a gripping portion 11 and a shank portion 12, the shank portion being screw-threaded for reception in a threaded opening in the

crown member 4. The gripping portion 11 is so formed as to cooperate with the studs 2 and 3 of the plunger nut C so that the standing valve may be removed from the 5 end-piece 9 if desired, but if the plunger nut is in engagement with the gripping portion 11 a seating of the standing valve will automatically disengage the gripping members so that the plunger and its plunger nut 10 may be withdrawn, leaving the standing valve seated. The member D is adapted to be received within the plunger nut C and the member D is formed with grooved portions 15 and 14, which grooved portions outline and form two peripheral members *a* and *b* built upon and integrally formed with a core member *c*. The members *a* and *b* are located on opposite sides of the core member *c* and the grooves or channels 13 20 and 14 are so formed as to cause the members *a* and *b* to terminate in pointed portions 15, which portions are not in alignment with the center line of the core *c*, and for reasons to be explained. The grooves 13 and 14 25 may best be described by describing how they form the members *a* and *b* and as the same includes two vertical portions 16 and 17 with a lateral portion 18, said lateral portion being undercut on an incline, as 30 shown at 19 and 20. The lateral portion 18 and the vertical portion 17 are joined by a curve 21 which terminates at a point beyond the point of junction 22 where the inclined or undercut portions 19 and 20 35 meet. The triangular pointed portions 15 of the members *a* and *b* are provided with inclined or beveled edges 23, which preferably are beveled downwardly toward the grooves 13 and 14. It is of course to be 40 understood in referring to the grooves and the particular form thereof, that the wall portions are referred to; that is to say, the walls formed by the grooves in the making of the core and the members *a* and *b*. 45 Assuming the position of the plunger nut C as shown in Figure 1, a dropping of the plunger and the plunger nut would cause the studs 2 and 3 to engage the beveled walls 23 of the members *a* and *b*, and as the 50 apexes of said triangular portions are off the center line of the core, the plunger nut is given a twist so as to direct the studs within the grooves 13, 14 and 16. This is diagrammatically illustrated in Figure 4, the 55 pointed lines in said figure illustrating components of force. A twisting or turning of the plunger will exert a pressure in the direction of the horizontal arrow and the lugs 2 and 3 of the plunger nut will be 60 directed to the grooves 17 of the members *a* and *b*. Assume now, that the lugs 2 and 3 are confined within the grooves 17, being limited in their movement by a top wall 24 of the members *a* and *b*, as shown in Figure 65 3. A dropping of the plunger with the

plunger nut will cause the studs 2 and 3 to follow the walls of the grooves 17, 21 and 18, turning the nut C and the plunger automatically. An upward pull upon the plunger might cause the lugs 2 and 3 to engage or miss the undercut wall 19 and in either case the lugs would be directed to the channel 16 and the plunger nut would be released from the member D. It will thus be seen that means have been provided whereby the plunger nut is automatically disengaged from the member D upon a lowering thereof. 70 75

It is obvious that a device of this character does away with the necessity of having any connection between the plunger and the standing valve. Consequently the plunger will reciprocate within given limits or may exceed those limits, or even contact with the standing valve and yet, unless the proper turn is given the plunger nut the standing valve will not be removed. Furthermore, the standing valve after being seated is automatically released from the plunger by allowing the plunger to rotate slightly and if it is desired to again remove the standing valve it is only necessary to lower the plunger so as to cause the plunger nut to engage the standing valve and a rotation of the plunger will cause the stud members connected with the plunger nut to ride within the grooves, as has been stated, and lock with the members *a* and *b* to remove the standing valve. 80 85 90 95

It is manifest that the invention will produce a great saving in time, incident to repair of the pump parts, and will enhance the length of life of the working parts of the pump. Furthermore, the particular construction shown with its center core *c* lends great strength in the structure. The various features incident to practicing the invention are simple and inexpensive in construction, and not liable to require frequent or troublesome replacement. 100 105 110

In standard practice the standing valve is removed or pulled out when the rods and plunger are removed, and all oil within the tubing flows back to its level. In the present invention the plunger, working valve 115 and rods may be removed, but the standing valve will still hold the oil in the tubing. Therefore there is a big saving in time and labor, inasmuch as when the plunger, working valve and rods are inserted back into 120 the tubing, the pump is primed and ready to produce. 125

It will be understood that many changes may be made in the construction, inter-relation, formation and association of parts, members and features, in the practice of the invention, and in the adaptation of the same to varying conditions of use and service, without departing from the true spirit of the invention. 130

Having thus disclosed my invention, I claim and desire to secure by Letters Patent:

1. In improvements of the character disclosed, a standing valve, a plunger, and a coupling for coupling said valve and said plunger to lift said valve, and for uncoupling said valve and plunger upon lowering said plunger after said valve has been seated; said coupling including a member formed with two spaced substantially vertical peripheral grooved portions connected by a curved peripheral groove, and a member adapted to traverse said grooved portions to lock said plunger and standing valve together upon turning said plunger in a given direction. 40
  - 10 2. In improvements of the character disclosed, a standing valve, a plunger, and a coupling for coupling said valve and said plunger to lift said valve, and for completely uncoupling said valve from said plunger automatically by lowering said plunger after said valve has been seated; said coupling including a member carried by said plunger, and a member carried by said standing valve, said member carried by said plunger being annular and provided with a 20 stud on its inner side, said member carried by said standing valve being provided with grooved portions adapted to receive said stud, a rotation of said plunger directing the stud along the grooved portions to effect an engagement between said plunger and said valve. 25
  3. In improvements of the character disclosed, a standing valve, a plunger and a coupling for coupling said valve and said plunger to lift said valve, and for uncou-
- pling said valve and plunger upon lowering said plunger after said valve has been seated; said coupling including a member formed with two spaced substantially vertical peripheral grooved portions connected by a curved peripheral groove, and a member adapted to traverse said grooved portions to lock said plunger and standing valve together upon turning said plunger in a given direction. 45
4. In improvements of the character disclosed, a standing valve, a plunger and a coupling for coupling said valve and said plunger to lift said valve, and for uncoupling said valve and plunger upon lowering said plunger after said valve has been seated; said coupling including a member formed with two spaced substantially vertical peripheral grooved portions connected by a curved peripheral groove, and a member adapted to traverse said grooved portions to lock said plunger and standing valve together upon turning said plunger in a given direction; a lowering of said last named member causing said member to traverse the curved wall of the curved peripheral groove to completely uncouple the plunger. 50
5. In testimony whereof, I have signed my name to this specification in the presence of two subscribing witnesses. 55
